SLIDING DOOR STRUCTURE FOR TUBS AND
THE LIKE

James N. White, Denver, Colo.

Application December 26, 1929
Serial No. 416,531

1 Claim. (Cl. 220—41)

This invention relates to doors for tubs and the like, and particularly to sliding door structures for tubs or containers constructed of wood or other material which changes in bulk when subjected to different conditions of moisture, and the invention is particularly, though not exclusively, adapted for use in wood stave cylindrical clothes containers used in laundry work.

An object of the invention is to provide in an article of the class described, a sliding door structure, the operation of which will not be affected by changes in bulk of the material of which the article is constructed, resulting from changes in the conditions of moisture to which the article is subjected.

A further object is to provide in an article of the class described, a rigidly spaced double sided runway for sliding door.

A further object is to utilize as part of the rigidly spaced, two sided runway above mentioned, the metal bands commonly used in binding together the staves of a wood tub of the class described and a spacing member such as that now in common use.

With the foregoing and other objects in view, all of which will more fully appear from the following specification and claim and the accompanying drawing, the invention comprises certain novel constructions, arrangements, and combinations of parts which will now be fully described and claimed and which are illustrated in the accompanying drawing, in which corresponding parts are indicated by like characters throughout the several views, and in which

Figure I is a view, in elevation, of a cylindrical wood stave clothes container, of a type in common use in laundry work, but showing the installation of the present invention therein.

Figure II is a section on line A—A of Fig. I looking in the direction of the arrow.

Figure III is a fragmentary section on line B—B of Fig. I.

Figure IV is a fragmentary section on line C—C of Fig. I.

Figure V is a view similar to Fig. III, but illustrating a modified structure, wherein the spacing element and one side of the runway are formed integral.

For the purpose of illustration and description of the present invention there has been used in the drawing, a perforated wood stave clothes container of a general type in common use in laundry machines, but it will be understood that the present invention will be equally applicable to any structure where a sliding door is desired

in an article which is subjected to changes in conditions of moisture and which is constructed of material, the bulk of which will undergo changes with such changes in moisture conditions, and with this explanation in mind the description of the invention will be given in terms of its application to the perforated wood stave clothes container, which is used as an illustration, it being understood that the invention as thus described can be applied to other objects of the class above indicated, with such changes only as will be obvious to those skilled in the art, in order to apply the invention to such other articles.

So far as the use of this invention in wood stave clothes containers in laundry machines is concerned, it is recognized that metal sliding doors have been used and are now in use, but such doors slide upon the outer surface of the wood staves and the runways are formed simply by the encircling metal bands with a spacing element to space such bands from the wood staves opposite the doorways and for the required distance to one side of the doorways to permit the sliding of the door. While such structures have been in use for a long time they are entirely unsatisfactory because the wood staves swell with the moisture and cause the doors to bind against the metal bands which form the outer side of the runways. As to clothes containers of this class the present invention consists in inserting beneath the encircling bands and beneath the spacing element, a metal strip which is embedded in the surface of the wood staves, but which projects above such surface to an extent just sufficient to raise the sliding door enough to allow the swelling of the wood staves and still to avoid contact of the swelled wood staves with the sliding door. To applicant's knowledge the objection to the use of sliding doors in the wood stave containers, because of the binding of the doors by the swelling of the wood, has existed for many years and, so far as applicant knows, without any successful effort to remedy the same, because such sliding doors which bind with the swelling of the wood are still in common use as the best construction known to the trade.

The clothes container above referred to and illustrated in the drawing, has disc ends 1, around which are positioned wood staves 2, bound together by metal bands 3 the ends of which may be overlapped and riveted as at 4.

For the purpose of affording access to the interior of the container the staves are cut away to form a doorway as at 5. In such of the con-

ainers now in use as have sliding doors, the bands 3 are spaced from the outer surface of the staves 2, by a spacing member in substance the same as the member hereinafter referred to by the numeral 7, and this spacing member spaces the band 3 away from the outer surface of the staves adjacent and at each end of the doorway and for a sufficient distance to one side of the doorway to permit the door to slide therein 10 for substantially the width of the door, thus opening the doorway.

In the present invention the staves are grooved beneath the band 3 and beneath the spacing member to a width preferably substantially the same as the width of the band 3 and for a length substantially the same as the length of the spacing member, and in the groove thus formed there is inserted a metal strip 6 substantially filling said groove but of a thickness slightly in excess 20 of the depth of the groove, whereby the upper surface of the strip 6 will project slightly above the outer surface of the wood staves adjacent the groove. All as clearly shown in Figs. III, IV and V.

25 The spacing member is indicated by the numeral 7.

The resultant structure is a runway adjacent each end of the doorway and extending for the desired distance to one side of the doorway, said runway consisting of two metal sides—one being the inner surface of the band 3 and the other being the outer surface of the strip 6, said two sides being rigidly spaced by the metal spacing member 7 positioned therebetween.

30 The door 9 is curved to conform to the outer contour of the container and its ends are positioned in the runways formed as above described, whereby the door may be slid in said curved runways, either to cover the doorways 5, as shown at the left in Fig. I, or to open the same as shown at the right in Fig. I. The rigid spacing of the two sides of the runway eliminates the binding of the edges of the doors in the runways, there being no material either in the door or in the 40 runway which swells because of moisture, whereby a permanent or unchanging sliding fit of the door in the runway is maintained.

The binding of the door by reason of the swelling of the staves between opposite runways, is 45 prevented by reason of the fact that the lower or undersides of the runways are slightly above the outer surface of the staves, so that even when the staves swell with moisture they will not contact with the undersides of the doors 9. By this 50 construction, therefore, a sliding door is provided which satisfactorily closes the doorway in a wood stave container, but the free sliding of which, in its runways, is assured without hindrance or binding resulting from the swelling of the staves 55 by moisture.

In positioning the spacer 7 under the bands at the ends of tub, the spacer will be placed to one side, as clearly shown in Figs. III and V,

thus leaving a runway 8 on one side of the spacer.

In the case of intermediate bands, that is bands which lie between two sliding doors, the spacer 7 will be placed centrally of the band 3 and strip 6, as clearly shown in Fig. IV thus leaving a 80 runway 8a on each side of the spacer 7.

It will be understood that the spacer 7 may be attached to the strip 6 or to the band 3 by screws or rivets, as indicated in Figs. III and IV, or the spacer may be formed integral with a band or strip, the integration of the spacer and strip 6 being illustrated at Fig. V.

In constructing a wood stave container with the present invention incorporated therein, it will be found convenient to first position the strip 6 in the staves. The spacer 7 is positioned either as an integral part of strip 6 or is attached thereto or is applied as a part of or attached to band 3, according to the construction used. The bands 3 are drawn tightly around the container and fastened in any suitable manner. The drawing of the band 3 around the container with the strip 6 and the spacer 7 therebeneath, will bind the strip 6 and the spacer 7 and band 3 into a unit of rigid construction, affording a rigidly spaced runway 8, or rigidly spaced runways 8a as the case may be, and such runways and the door 9 sliding therein, will be unaffected by changes in bulk of the wood staves, resulting from subjection of the staves to moisture.

105 It will be noted that in the embodiment of this invention illustrated in the drawing, there will be a slight triangular space at each end of the spacer 7 between the wood staves 2 and the band 3, this space being indicated at 10 in Fig. II. The space has no particular purpose, but is an incident to the construction herein described. It may be filled in any suitable manner if desired.

110 Changes in detail of construction, within the 115 spirit and scope of the foregoing specification and the appended claim will occur to those skilled in the art.

I claim:

120 In a circular container composed of pieces of material whose bulk is affected by moisture and having encircling bands adapted to hold said pieces together and having doorways in said container between said bands and doors for said doorways, the improvement comprising in combination strips beneath said bands and embedded in said pieces but projecting slightly above the surface of said pieces and spacers between said bands and said strips, whereby said combined bands, spacers and strips are adapted to both retain said pieces together and form runways for said doors spaced away from the surface of said pieces sufficiently to permit said doors to slide in said runways over said surfaces without contact with said surfaces when said pieces are expanded, said bands, spacers and strips being of material whose bulk is not affected by moisture.
